UNITED STATES PATENT OFFICE.

JOHN L. COBB, OF LOS ANGELES, CALIFORNIA.

ELECTRIC COUPLING.

1,122,193.

Specification of Letters Patent. Patented Dec. 22, 1914.

Application filed July 21, 1913. Serial No. 780,220.

To all whom it may concern:

Be it known that I, JOHN L. COBB, a citizen of the United States, residing at Los Angeles, in the county of Los Angeles, State of California, have invented new and useful Improvements in Electric Couplers, of which the following is a specification.

This invention relates to train couplers, and particularly to train pipe couplers equipped with electric coupling means for connecting up the various electrical circuits throughout the length of the train; and the invention consists in certain combinations and in certain specific details which will be hereinafter pointed out.

One of the features of my invention is the combination of an electrical contact mechanism with a fluid pressure coupling mechanism, so that the contacts are pressed together when the fluid couplers are pressed together; and a feature is the arrangement to give the contacts a relative movement in the plane of their engaging surfaces by operation of the air pressure which is admitted to and through the coupler when in proper engagement. To effect this relative movement I prefer to have the contact heads revolvable in the plane of their engaging faces, and I employ a simple mechanism operable by the fluid pressure passing through the fluid pressure duct of the coupler to give the contact head a small relative rotation when they are pressed together.

In the accompanying drawings, I have illustrated my improved form of train-pipe coupler; and it will be seen that any other form of coupler, which accomplishes the operations to be hereinafter described, will be sufficient. I shall describe my improved form of coupler in-so-far as it may coöperate with my electrical contact mechanism.

In the accompanying drawings, Figure 1 is a longitudinal section showing my improved form of coupler and my electrical contact mechanism, the two opposite coupling elements being shown in the operation of engaging with each other. Fig. 2 is a section taken as indicated by line 2-2 of Fig. 1.

In the drawings, I have shown a pair of coupling members or elements designated generally by the numerals 10 and each con-

sisting of a frame 10^a and a pivoted pressure carrying box 10^b. Each frame 10^a is made up of a guide tongue 11 and a throat 12, the throat of each member adapted to receive the guide tongue of the other. Each frame has a surface 13 against which the forward end of a block 14 of the other frame is adapted to abut, thus limiting the movement of the members toward each other in a longitudinal direction.

The pressure carrying boxes 10^b are each pivoted at 20 so that they may have a small pivoted movement on their frames, so that there may be a small space between their engaging faces 21 as the couplers move together longitudinally. Each of the pivoted pressure carrying boxes 10^b has a yoke 22 having a lip 23 thereon, which lip is adapted to engage in a depression 24 in the tongue 11 when the couplers are in their interlocking position. As the couplers move together it will be seen that the outer faces of the tongues 11 move over the lips 23, so that the pressure carrying boxes 10^b are thrown away from each other, until the coupling elements reach their final positions. Then the lips 23 engage in the notches 24 and the pressure carrying boxes may move inwardly toward each other. This movement is positively accomplished by the ends 11^a of the tongue riding up over surfaces at the rear ends 11^b of the pivoted pressure carrying boxes. Thus, when the couplers come into correct longitudinal position, the pressure carrying boxes are forced laterally or transversely together, their surfaces 21 co-engaging, and the lips 23 are forced into notches 24 so that the coupler elements are held against being pulled apart. After the coupler elements are engaged in this manner, fluid pressure is admitted to the interior passage ways or ducts 35 of the boxes 10^b, and this air pressure, or any other fluid pressure, acts upon diaphragms 36, which then press outwardly against the tongues 11, pressing the tongues into engagement with the lips 23, and at the same time pressing the boxes away from the tongue and pressing them together.

Each of the boxes 10^b can contain as many compartments or passages 35 as is necessary; and in my preferred form of construction I utilize the central passage 35 for passage of

- train pipe air, while I use the upper compartment 35^a for my electrical contact mechanism. This electrical contact mechanism may comprise as many contact heads 40 as may be desired; I have shown a mechanism containing four contact heads 40 mounted upon four contact stems 41 which are placed in the compartment 35^a at right angles to the contacting face of the box 10^b. These stems 41 are preferably supported in insulated bearings in any preferred manner; and they are pressed forwardly toward the contact face 21 by a suitable spring 42. When pressed forward by the springs 42, the contact heads 40 are pressed slightly beyond the contact surface 21; and sufficient backward movement of the contact heads is allowed so that, when the corresponding contact heads of opposite coupler elements engage and are pressed against each other, the pressure will be taken up by the springs 42. It will be understood that the contact heads do not project sufficiently to strike or rub over each other as the coupler elements move together longitudinally; that they are only brought together by the transverse movements of the pressure carrying boxes when they are in correct opposite position.
- Surrounding each contact head is a plastic gasket 43, preferably made of soft rubber. These gaskets project beyond the surfaces 21, about flush with the outer contact faces of contacts 40, and are adapted to engage and to be pressed together when the boxes 10^b are pressed together. Pressing these soft rubber gaskets together causes them to fill the spaces in which they are placed very tightly and to tightly press against contact heads 40 thus forming moisture proof joints which will prevent entrance of moisture to the compartments 35^a. This is an important feature as it prevents access of moisture to the electrical connections within the compartments.
- Each of the stems 41 has an arm 50 which engages in any suitable manner with piston rod 51. I may use any form of means operable by air pressure in the ducts 35, but I prefer to use a piston 52 mounted upon the piston rod 51 and mounted within a small cylinder 53, there being a suitable gasket 54 which is struck by the piston, 52 at the end of its pressure impelled movement, so as to make a tight nonleaking joint when the piston reaches the end of its movement. A suitable spring 55 presses the piston and piston rod oppositely against the pressure induced movement keeping them in the normal position shown in Fig. 2. When pressure is admitted to the passage 35, as it is after the coupling elements are interlocked, the piston 52 will move upwardly and will cause the rotation of the contact heads 40. The contact heads will rotate in the opposite directions against

each other, so that a good sliding or rubbing engagement is obtained between them which tends to clean the contact heads each time a contact is made.

It will be understood that the purposes of my invention are fulfilled by giving the contact heads a relative movement in the plane of their contacting surfaces; and I may either cause this relative movement by moving only one set of the contact heads or by moving both sets of contact heads. I prefer to move both sets of heads and to move them in opposite directions, as this makes the coupling elements all symmetrical and duplicates of each other. 80

Having described a preferred form of my invention, I claim:

1. In a train-pipe coupler, a pair of interlocking coupler elements and means for pressing said elements together, revoluble 85 contact heads on the elements situated opposite each other to be pressed into engagement by the pressing together of said elements, and means to give a relative rotary movement to said contact heads. 90

2. In a train-pipe coupler, a pair of coupler elements and means for pressing said elements together, coöperating movable contact heads mounted oppositely on the coupler elements with contact faces adapted to 95 co-engage, and means to move said contact heads relatively to each other in the plane of their engaging faces.

3. In a train-pipe coupler, a pair of coupler elements, having fluid pressure passages therethrough, means for pressing said elements into engagement with each other, co-operating movable contact heads mounted oppositely on the coupler elements with contact faces adapted to co-engage, and means 100 operable by fluid pressure in the coupler elements to move said contact heads relatively to each other in the plane of their engaging faces. 105

4. In a train-pipe coupler, a pair of coupler elements having fluid pressure passages therethrough, means for pressing said elements into engagement with each other, co-operating rotatable contact heads mounted 110 oppositely on the coupler elements with contact faces adapted to co-engage, and means operable by fluid pressure in the coupler elements to give said contact heads a relative rotation in the plane of their engaging faces. 115

5. In a train-pipe coupler, a pair of coupler elements having fluid pressure passages therethrough, means for pressing said elements into engagement with each other, co-operating rotatable contact heads mounted 125 oppositely on the coupler elements with contact faces adapted to co-engage, and means operable by fluid pressure in the coupler elements to give said contact heads a relative rotation in the plane of their engaging 130.

- faces, said means embodying a movable member having a face exposed to fluid pressure in each coupler element, and connecting means between said member and the corresponding contact head.
6. In a train-pipe coupler, a pair of coupler elements having fluid pressure passages therethrough, means for pressing said elements into engagement with each other, co-operating rotatable contact heads mounted oppositely on the coupler elements with contact faces adapted to co-engage, and means operable by fluid pressure in the coupler elements to give said contact heads a relative rotation in the plane of their engaging faces, said means embodying movable pistons having one end exposed to fluid pressure in said passages, means to move said pistons against the fluid pressure, and connecting means between the pistons and the corresponding contact heads to cause rotary movement of the heads by virtue of movement of the pistons.
7. In a train-pipe coupler, a pair of inter-engaging coupler elements adapted to move together longitudinally and having fluid passages therethrough, means operated by fluid pressure in said passages to press said elements together, contact heads movably mounted on the elements opposite each other and adapted to be pressed into engagement by the elements being placed together, and means operable by fluid pressure in said passages to move said contact heads relatively to each other.
8. In a train-pipe coupler, a pair of inter-engaging coupler elements adapted to move together longitudinally and having fluid passages therethrough, means operated by fluid pressure in said passages to press said elements together, revolute contact heads mounted on the elements opposite each other, having faces adapted to co-engage by virtue of the elements being pressed together, and means operable by fluid pressure in said passages to rotate said contact heads relatively to each other in the plane of their engaging faces.
9. In a train-pipe coupler, a head having therein a chamber to receive air pressure, and an adjoining chamber having electrical mechanism with stems which project through the contacting wall of the coupler head, and means between said chambers for imparting a motion of revolution to the contacting stems by the air pressure in the air chamber.
10. In a train-pipe coupler, a head having a chamber adapted to receive air pressure, an adjoining chamber having electrical mechanism therein, stems connected with said electrical mechanism projecting through the contact wall of said head, resilient means for keeping said contact stems of one head in engagement with the contact stems of an abutting head, and means for revolving said stems by the air pressure in the adjoining air chamber.
11. In a train-pipe coupler, a head provided with an air pressure chamber, and an adjoining chamber containing therein stems which project through the contact wall of the head, each of said stems being revolubly mounted in the head, a piston rod connected with said stems, the end of the piston rod having a piston head, a partition wall between the two chambers having a cylinder therethrough adapted to receive the piston head whereby the pressure of air in the air chamber will longitudinally move said piston and cause movement of said stems.
12. In a coupler, a pair of interlocking coupler frames adapted to move longitudinally into interengagement with each other, co-operating contact heads mounted on the frames to be transversely movable thereon, means operated by the relative movement of the frames into interlocking position to hold said heads apart during said movement and to force said heads together at the end of said movement, and means for moving said contact heads relatively to each other in the plane of their engaging faces.
13. In a coupler, a pair of interlocking coupler frames adapted to move longitudinally into interlocking engagement with each other, contact carrying members transversely movable on said frames, co-operating contact heads in opposing faces of said members to hold said members transversely apart during the interlocking movement of the frames and to force said members together at the end of said movement, and means to move said contact heads relatively to each other in the plane of their engaging faces.
14. In a coupler, a pair of interlocking frames adapted to move longitudinally into interlocking engagement with each other, a joint forming member pivoted to each frame, said members adapted to move transversely on their respective frames to and from each other, co-operative contact heads carried in opposing faces of the joint forming members, means for holding the joint forming members and heads apart during interlocking movement of the frames and for forcing said members and heads transversely together at the completion of said movement, fluid pressure operated means to force the joint forming members and heads together, and fluid pressure operated means to move said contact heads relatively to each other in the plane of their engaging faces.
15. In a coupler, a pair of interlocking frames adapted to move longitudinally into interlocking engagement with each other, a joint forming member pivoted to each frame, said members adapted to move transversely on their respective frames to and from each other, co-operative contact heads carried in opposing faces of the joint forming members, means for holding the joint forming members and heads apart during interlocking movement of the frames and for forcing said members and heads transversely together at the completion of said movement, fluid pressure operated means to force the joint forming members and heads together, and fluid pressure operated means to move said contact heads relatively to each other in the plane of their engaging faces.

from each other, coöperative contact heads carried in opposing faces of the joint forming members, means for holding the joint forming members and heads apart during 5 interlocking movement of the frames and for forcing said members and heads transversely together at the completion of said movement, fluid pressure connection to the joint forming members, fluid pressure operated means carried by the members to press against the interlocking frames and force the members and heads together, and fluid

pressure operated means mounted in the said members adapted to cause relative movement of the heads in the plane of their 15 engaging faces.

In witness that I claim the foregoing I have hereunto subscribed my name this 14th day of July, 1913.

JOHN L. COBB.
